CLIP FOR SECURING DRAFT EXCLUDING OR SEALING STRIPS

Thomas John Robert Bright, Leek Wootton, near
Warwick, England

Application July 15, 1954, Serial No. 31,447

Term of patent 14 years

(Cl. D54—11)

Fig. 1 is a rear perspective view of a clip for securing draft excluding or sealing strips, showing my new design.

Fig. 2 is a plan.

Fig. 3 is a side elevation.

Fig. 4 is a front and bottom perspective view.

I claim:

The ornamental design for a clip for securing draft excluding or sealing strips, as shown.
